US00D534358S

(12) United States Design Patent (10) Patent No.: US D534,358 S
(45) Date of Patent: * Jan. 2, 2007

(54) TEXTILE

- (75) Inventor: Jong Hee Lee, Goyang (KR)
(73) Assignee: Korean Airlines Co., Ltd., Seoul (KR)
() Term: 14 Years
(21) Appl. No.: 29/242,041
(22) Filed: Nov. 4, 2005
(30) Foreign Application Priority Data
Sep. 12, 2005 (KR) 30-2005-0030943

(51) LOC (8) Cl. 05-05
(52) U.S. Cl. D5/58

(58) Field of Classification Search D5/1-3,
D5/5, 7-8, 11, 13-16, 19-20, 23-28, 30,
